UNITED STATES PATENT OFFICE.

CHARLES E. MacKUSICK, OF CAMBRIDGE, MASSACHUSETTS.

DESIGN FOR A DISPENSING-RECEPTACLE.

41,491.

Specification for Design.

Patented June 20, 1911.

Application filed September 23, 1910. Serial No. 583,523. Term of patent 7 years.

To all whom it may concern:

Be it known that I, CHARLES E. MacKUSICK, a citizen of the United States, residing at Cambridge, in the county of Middlesex and State of Massachusetts, have invented a new, original, and ornamental Design for Dispensing-Receptacles, of which the following is a specification, reference being had to the accompanying drawing, forming part thereof.

The figure is a view in perspective of a dispensing receptacle showing my new design.

I claim:

The ornamental design for a dispensing receptacle, as shown.

CHARLES E. MacKUSICK.
